WILLIAM M. VENABLE, OF PITTSBURGH, PENNSYLVANIA, ASSIGNOR TO BLAW-KNOX COMPANY, A CORPORATION OF NEW JERSEY.

BATCHING APPARATUS.

Application filed November 7, 1922. Serial No. 599,529.

- My invention relates to what may conveniently be termed batching apparatus, and more particularly to apparatus for keeping separate and delivering or dumping as 5 wanted different materials that are to be used concurrently or together. Examples of such batching apparatus are the bodies of motor trucks used for hauling ingredients for concrete.
- 10 Various objects and advantages of the invention will appear from my explanation hereinafter of its use in connection with concrete work on roads and the like, and from my description of the best embodiments of 15 the invention known to me with special reference to their use in road building.
- In building concrete roads and road foundations, it is customary to grade the roadway with a steam shovel or the like a long dis- 20 tance ahead of the actual paving work: indeed, it is quite common to have the grading practically completed (except for the final finishing up and levelling of the surface) several miles ahead of the actual con- 25 creting operations. The roadway is usually graded just to the width necessary to receive the pavement, which for concrete roads is generally about 18 feet, more or less; so that at the point where the mixer is operating 30 and the concrete being placed in the roadway, very little extra room is available. Generally, of course, the materials for the concrete have to be hauled over the graded roadway ahead of the mixer (and of the 35 fresh concrete just placed on the grade); and to avoid congestion in the limited space where work is going on around the mixer, it is customary to drive motor trucks with the mineral aggregate that is to be mixed 40 with cement to form the concrete within one or two hundred feet of the mixer (where a turntable is generally provided to turn them around), and then back them up to the mixer and dump their loads into the latter.
- 45 In present practice, the mineral aggregate for each charge of the mixer generally consists of about 12 cu. ft. of sand and 18 cu. ft. of broken stone or gravel. Small trucks haul only one such batch of sand and stone 50 at a load; others, large enough to carry several such batches, are provided with cross partitions to divide them up into separate compartments for the batches. After dumping its first batch into the mixer hopper, such 55 a truck is drawn a few feet away to await
- disposal of this batch by the mixer before backing up to it again and depositing another batch—and so on until all the batches in the truck (up to a maximum of four, according to present practice) have 60 been dumped.
- The cement used in the concrete is not hauled in the same batch with the sand and stone, because the latter are more or less wet, and hence likely to injure the cement 65 in transit. In order to obviate the congestion, inconvenience, and delay that would result from periodically unloading trucks of cement right at the mixer as required, it is customary to haul the cement independ- 70 ently of the mineral aggregate, and to store it in piles along the side of the grade. As a great deal of cement is required, and as it cannot well be "planted" in this manner very far ahead of the mixer—on account of 75 its deterioration with prolonged exposure or in case of rain—this separate hauling proves a great nuisance; for it necessarily causes congestion and interferes with the free and undelayed stream of stone and sand trucks 80 to and from the mixer on which regular, continuous, economical operation depends. And besides the labor and expense of loading, hauling and unloading and placing the 85 cement along the roadway, this practice requires the continuous services of some four extra men at the mixer (when the latter is of ordinary size) to handle the bags of cement and empty them into the mixer,—to say nothing of the annoyance and trouble of 90 gathering the sacks and hauling them back to the warehouse, the considerable loss of sacks by carelessness, and the occasional damage to the cement (in transit or along- 95 side the roadway by wetting).
- My invention makes it possible to do away with such disadvantages of present practice, by abolishing the separate hauling of cement. Even though the stone and sand be reeking wet, my invention permits the ce- 100 ment to be hauled in the same truck with them without any risk of dampening. It makes it possible to do away with handling of cement or sacks along the roadway or at the mixer, and allows all handling and 105 emptying of sacks to be done at the warehouse, by the same force and in the same time now required to load the cement on the trucks that are used to haul it separately to the field of operations.

In the drawings, Fig. 1 is a diagrammatic side view of a motor truck body inclined or tilted to dumping position, the truck chassis and other parts being indicated in broken lines, and certain parts being broken away to expose various features of apparatus conveniently embodying my invention.

Fig. 2 is a fragmentary side view somewhat similar to Fig. 1, but on a larger scale, 10 showing the truck body horizontal.

Fig. 3 is a fragmentary view as from the right of Fig. 2 showing the truck body in cross section, certain parts being omitted.

Figs. 4 and 5 show fragmentary horizontal 15 sections taken as indicated by the lines 4-4 and 5-5 in Fig. 2.

Figs. 6 and 7 are fragmentary side views illustrating a modified construction, the vehicle body being in longitudinal section 20 in both views,—in one horizontal, and in the other inclined or tilted for dumping.

The truck and the provisions for elevating or tilting its body 10 for dumping (see Fig. 1) may be of any preferred type and construction. As shown, the body or container 25 10 is in the form of a rectangular "box" open at top and rear, and affords two separated containers or compartments 11 and 12 for the two batches of sand and stone 30 that it has capacity to carry. Ordinarily, the rear sides or ends of the compartments 11 and 12 are closed, and their contents retained even after the body 10 is tilted, by means of closure or partition structures or 35 devices 14, 15. Containers or compartments 16, 17 (likewise counterparts of one another) are provided for separate transportation of the cement to be used with each batch of sand and stone. As here shown, these auxiliary cement compartments 16, 17 are associated and in a manner combined with the closure or partition devices 14, 15, as unitary structures that can very easily be installed 40 in or removed from almost any truck body 45 10, and can readily be substituted for the usual partitions of trucks heretofore in general use. The entire devices or structures 14, 15 here shown being just alike, and similarly mounted in the body 10, it will 50 suffice to describe the former.

Referring, now, to Figs. 1, 2, 3, 4 and 5, it will be seen that the auxiliary compartment 16 of the device 14 is in the form of a transverse sheet metal pocket with upright 55 side wall 18, ends 19, and bottom 20,—the latter in the present instance sloping rearward somewhat, as shown, and being preferably of heavier plate, on account of the extra severe abrasion and wear to which it 60 is subjected. To close the upper end or top of the compartment 16 and provide conveniently for filling it with cement, a sheet metal cover 21 (with downturned or flanged edges to overlap the compartment walls and 65 make a weather-proof joint) is hinged on a

transverse pivot rod 23 extending across the forward upper edge of the pocket and mounted in brackets or clips 24 secured to the compartment walls. At one side of the compartment 16 is a transversely extending 70 metal plate 25 which not only forms its lateral wall, but also closes the whole rear side or end of the main compartment 11 with which the structure 14 is functionally associated. This plate 25 is movable to serve 75 as a discharge gate for the main compartment 11, and also controls the discharge from the compartment 16. As shown in Figs. 2 and 3, the plate 25 is suspended to swing fore and aft in the body 10, from a pivot rod 80 26 extending across the body, and itself mounted as hereinafter described. In the construction here illustrated, the compartment walls 18, 19, 20 are fixedly mounted relatively to the body 10, and the plate 25 is 85 at the rear side of the compartment 16 and serves directly as gate therefor, as well as for the compartment 11.

The gap that would otherwise exist between the upper edge of the plate 25 and the 90 top of the cover 21 is closed by a transverse plate 27 secured at its ends to the walls 19, and of sufficient width to be slightly but closely overlapped and pressed against by the upper edge of the plate 25; and further 95 protection against the weather is afforded at this point by a sort of overhanging curved sheet metal eaves 28 secured to the plate 27.

It will be seen, therefore, that so long as the gate 25 remains in the closed position 100 shown in Figs. 2 and 3, the materials in the two compartments 11 and 16 are held and kept separate and out of contact with one another, without opportunity for the one to become wet from the other, and the contents 105 of the compartment 16 are also fully protected from the weather. When, however, the truck body 10 is tilted and the gate 25 released to swing and open rearward and outward under the influence of gravity as shown in Fig. 1, free passage is afforded for the gravitational discharge of the sand and stone from the compartment or container 11 beneath the compartment or container 16 and the gate 25. At the same time, also, 110 the cement from the compartment 16 is likewise automatically released and discharged downward upon, into, and with the rush of sand and stone, and carried with them into the mixer. Thus there is no chance for the cement to stick to the wet interior of the body 10, because it never comes in contact therewith; while the sand and stone not only make 115 a clean sweep of everything into the mixer, but also exert a scouring and cleaning effect 120 on the interior of the body.

The phenomena when the other compartment 12 is discharged are the same,—except, of course, that its contents have further to slide.

Passing, now, to other features and details of construction and operation, it will be observed, in the first place, that the gate plate 25 is reinforced and stiffened around its outer edges by external angle bars 30, and elsewhere by external vertical angle bars 31 and internal horizontal V shaped sheet metal stiffeners 32 and 33. The last of these, it will be seen, seats and makes a tight joint 10 against the bottom plate 20 when the gate 25 is closed, as shown in Fig. 2. When the gate 25 closes, it also seats more or less closely against the edges of inward joggled vertical plates 34 secured to the compartment walls 19; and this joint is additionally protected 15 and made practically tight by vertical sealing angle flanges 35, 35 on the gate that close on either side of each plate 34.

As shown in Figs. 2, 3, 4 and 5, the gate 25 is normally held closed by engagement 20 of inward projecting bevel-ended latch hooks 36 at its vertical edges over the edges of catch notches 37 in the bottom plate 20 within the narrow vertical chambers formed 25 within the compartment 11 by the plates 34. When the gate is to be opened, the latches 36 can be disengaged and released by lifting them out of the notches 37. As shown, this is 30 accomplished by lifting the ends of the gate pivot rod 26, which extend through vertical guide slots 38 in angle bar brackets 39 secured to the compartment walls 19 above the body 10, and projecting rearward. As a convenient means of lifting the ends of this rod 35 26 together (and thus releasing the latches 37, 37 simultaneously), an eccentric 40, with handle 41, is non-rotatably secured to each end of the rod, so as to bear on the outward projecting horizontal bracket flange. Thus 40 the gate 25 may be released and opened or set to lock itself shut on closing by manipulating either handle 41 as most convenient at the moment.

When the eccentrics 40 are in locking adjustment, the handles 41 extend forward beside the brackets 39 (Fig. 2); while for releasing adjustment, they extend rearward in a conspicuously exposed position (Fig. 1). The weight of the handles 41 and of the gate 50 25 itself naturally prevents release of the gate 25 by jarring, and flats 42 on the eccentric peripheries prevent partial and dangerously deceptive accidental closing rotation of the eccentrics when once set for release.

While, of course, the various wall plates 18, 19, 20 and 27 and the gate 25 might be 60 more or less separately secured to the truck body 10 (in which case the lower portions, at least, of the plates 19 could be dispensed with), it is generally preferable to secure all these parts together independently of the body 10, as shown, so as to form one complete unit that can be easily and quickly 65 mounted and secured in proper position in the body. By designing the compartments 16, 17 of ample depth and capacity and merely varying their mounting in the body 10, the structures 14, 15 can be standardized as to cross section or profile for truck bodies 70 of a great many different shapes and styles; so that in order to adapt the standard line or design to extreme variations in truck width, it will only be necessary to vary the lengths of the pieces 18, 20, 21, 25, 27, etc., 75 transversely of the body, which as a manufacturing proposition is generally much simpler and easier than to modify the profile.

A convenient method of mounting the units 80 14, 15 in the body 10 is to employ longitudinally extending angle bars 44 that can be secured to the usual top flanges 45 of the body with their own upstanding flanges to the inside, so that the units 14, 15 (and as many 85 more like them as the size of the body 10 may demand) can be fitted between such flanges and secured to them by bolts 46 extending through the compartment walls 19. Thus the entire structure 14 or 15 can be 90 easily and quickly removed for repair, or to permit use of the truck without it. Minor variations in width of bodies 10 or length of compartments 16, 17 can easily be accommodated or compensated for by interposing 95 filler pieces 47 of appropriate thickness between walls 19 and angle bars 44, or by altering the width of the horizontal flanges of the bars 44 or their position on the body flanges 45, or both. Variations of bodies 10 100 in depth can be taken care of in the manner indicated above, by merely varying the vertical position of the row of holes for the bolts 46 in the compartment walls 19 so as to give the proper depth of opening 105 (some 6 or 8 inches, say) below the compartments 16, 17, and the proper working clearance at the lower edges of the doors 25.

In Figs. 6 and 7, I have marked various parts and features with the reference characters applied to corresponding ones in Figs. 1 to 5, as a means of dispensing with merely repetitive description. Here the gate plate 25 is at the forward side of the auxiliary 110 pocket compartment or container 17 illustrated, and the latter is attached directly to the plate 25, so as to swing with it, and in a sense form part of the very gate itself. Accordingly, the entire structure 15 is 115 pivoted to the angle bars 44 on the body flanges 45, as by means of a transverse rod 50 extending through holes in said angles 44 and in horizontal bracket pieces 51 secured to the compartment walls 19. While the gate plate 25 still controls the compartment 17 and its downward discharge, it no longer does so directly as in Figs. 1-5. On the contrary, a separate closure or door is provided for the lower end of compartment 17, in the form of a swinging 125 130

bottom plate 52 with its own forward edge hinged or pivoted at 53 to the plate 25. So long as the gate 25 remains closed, as shown in Fig. 6, the "trap" door 52 is also held closed by the truck body bottom; but when the gate and compartment or container structure 15 swings and opens rearward or outward (by gravity) to afford free passage therebeneath for the sand and stone 10 from the compartment 12, the door 52 automatically drops open and discharges the cement in the compartment 17 upon, into, and with the discharge from the compartment 12,—just about as already described.

15 When, on the other hand, the gate 25 swings forward to close, the trap door 52 is swung upward and closed by engagement with the truck body bottom. Obviously, the structure 15 can be very easily removed 20 from the body 10 for any purpose on simply withdrawing the pivot rod 50.

As shown, the plate 52 is reinforced and stiffened transversely with transverse angles 25 54, and longitudinally by a longitudinal V or U shaped sheet metal stiffener 55. When the gate 25 and the trap door 52 close, the member 55 slides on the body bottom and forces the plate 52 close up against the edges of the compartment walls 19 and 30 against the edges of inward sloping metal "lip" strips 56 secured and extending transversely of the body near the lower edges of the walls 18 and 25. When the gate 25 is closed, additional protection at these points 35 of sealing may be afforded by extension of the plate 18 down close to the bottom of the body 10, and by a forward-joggled skirt plate 57 attached to the plate 25 above the pivot 53. Normally and until the contents 40 of the compartment 12 are to be dumped, the gate 25 and the associated compartment 17 are held closed by one or more locking rods or pins 58 extending through holes in the angle bars 44 and in the rearward projecting extremities of the bracket plates 51.

I claim:

1. The combination of a dumping container, and a lateral closure structure therefor, said closure structure comprising a gate for controlling the discharge from the container and also comprising an auxiliary compartment.
2. The combination of a dumping container, and lateral closure and discharge means therefor comprising an auxiliary compartment affording passage therebeneath for the discharge of material carried by said container, and itself discharging into such material.
3. The combination of a container and lateral closure and discharge means therefor comprising an auxiliary container automatically discharging into and with the contents of that first-mentioned when such contents are discharged by said means.

4. The combination of a dumping container, a lateral closure and discharge gate therefor, and means co-operating with said gate to form an auxiliary container controlled by the gate. 70

5. The combination of a dumping container, a lateral gate therefor pivoted to swing and open outward and thus discharge the contents of said container therebeneath, and means cooperating with said gate to 75 form an auxiliary container automatically discharged when said gate swings outward and discharges as aforesaid.

6. The combination of a tilting dump body, a gate pivoted thereacross to swing 80 outward and discharge the contents thereof while the body is tilted, and means co-operating with said gate to form a compartment with a passage therebeneath, when the gate opens, for the discharge from said 85 body as aforesaid, and with downward discharge for its own contents also controlled by said gate.

7. An auxiliary compartment structure 90 for a tilting dump body, said structure comprising a gate adapted to control both the discharge from such body and also that from the auxiliary compartment.

8. An auxiliary compartment structure 95 adapted to be mounted in a tilting dump body, said structure comprising a discharge gate for such body and being adapted to discharge its own contents automatically when said gate is opened.

9. The combination of a dump body container, and an auxiliary compartment swingable thereon to discharge its own contents, with means for normally locking said compartment relative to said body to prevent such discharge. 100

10. The combination of a dump body container, and an auxiliary compartment swingably mounted thereon and having a swinging end closure for discharging its contents, with means for normally preventing swinging 110 of said compartment and discharge of its contents as aforesaid.

11. The combination of a dump body container, and an auxiliary compartment swingably mounted thereon and having swinging 115 closures at top and bottom, with means for normally preventing swinging and discharge of said compartment.

12. The combination with a tilting dump body container, of an auxiliary compartment 120 movable to afford free passage therebeneath for discharge of material from said container, and itself automatically discharging into and with such material.

13. The combination with a tilting dump 125 body container and a gate for discharging its contents when the body is tilted, of an auxiliary compartment movable to afford passage therebeneath for discharge of material from said container, and provided 130

with a door mounted to open automatically when the container gate is opened and the compartment moves as aforesaid.

14. The combination with a dump body 5 container, of an auxiliary compartment mounted to swing outward and afford passage therebeneath for discharge of material from said container, and a bottom door for said compartment normally held shut by engagement with the bottom of said container, 10 but mounted to swing open downward when said compartment swings outward as aforesaid.

15. The combination with a dump body 15 container and its closure and discharge gate, of an auxiliary compartment affording passage therebeneath for discharge of material from said container, and itself adapted and arranged to automatically discharge its contents between the portions of such material 20 first and last discharged when said gate is opened.

In testimony whereof I have hereunto signed my name.

WILLIAM M. VENABLE.
